UNITED STATES PATENT OFFICE.

JOHN HEBERLING, OF ROCHESTER, NEW YORK.

PIN-WHEEL TOY.

Application filed May 23, 1925. Serial No. 32,500.

The object of the invention is to provide a new and improved pinwheel toy.

This and other objects of this invention will be fully illustrated in the drawings, described in the specification and pointed out in the claims at the end thereof.

In the accompanying drawings:

Figure 1 is a front elevation of the pin and wheel toy.

10 Figure 2 is a rear elevation thereof.

Figure 3 is a side elevation of a slightly modified form of the pin wheel toy.

Figure 4 is a front elevation thereof.

Figure 5 is a horizontal sectional view of

15 the bearing and pivot member of the pin wheel toy illustrated in Figures 3 and 4, the section being taken on the line 5^x—5^x of Figure 3.

Figure 6 is a side elevation of another 20 modified form of the pin wheel toy.

Figure 7 is a front elevation thereof.

Figure 8 is a horizontal sectional view of the bearing and pivot members of the pin wheel toy illustrated in Figures 6 and 7.

25 Figure 9 is a front elevation of a modified form of the pin wheel.

Figure 10 is an enlarged vertical sectional view of the central portion of the pinwheel 30 illustrated in Figure 9 and its mounting on the supporting rod thereof.

Figure 11 is a front elevation of another form of construction of the pin wheel.

Figure 12 is an enlarged sectional view 35 of the central portion of the pin wheel illustrated in Figure 11.

In the several figures of the drawings like reference numerals indicate like parts.

It has been found that the pin wheel toys 40 in which the power of a pinwheel rotated by

a current of air, is utilized to operate a moving toy, such as have heretofore been made and sold, need a strong current of air for their operation. This is objectionable in toys of this nature as a child operating it has to

45 continuously run or at least walk fast in order to make an air current that is strong enough to turn the pin wheel and drive the toy. The pin wheel toy forming the subject matter of my present invention eliminates

50 this trouble as it is so constructed that the friction of the rotating and moving parts

are greatly reduced. The pin wheel and the figure are mounted in such relation to each other and are counterbalanced in such a way that the pin wheel spins very freely and rotates the toy in the slightest air current. 55

As illustrated in the figures of the drawings, this has been accomplished by providing the pin wheel among other things with a long bearing sleeve 1 that passes with one 60 end thereof thru the supporting stick 2 near the upper end. In the long bearing formed by this sleeve is mounted to rotate the shaft or axle 3 having a crank 4 formed at one end thereof and being turned up and into 65 engagement with the pin wheel 5 with the other end thereof. The inner bearing of the pin wheel 5 is mounted to rotate on the sleeve 1 while the outer bearing may also be mounted to rotate thereon as illustrated in Figure 70 5 or may be mounted on the outer end of the shaft or axle 3 with which it rotates as illustrated in section in Figure 8.

The end of the shaft 3 which engages the pin wheel may be made to engage into a hole 75 provided in one of the blades of the pin wheel or it may be made to engage between two of the blades at or near their junction in order to form a positive connection between the pin wheel and the shaft that will 80 cause the pin wheel positively to rotate the shaft and operate the toy connected thereto.

The mounting of the pin wheel and its connection to the shaft is thus made very simple and as both the front and rear bearings of the pin wheel are metal bearings 85 and rotate on metal surfaces the pin wheel rotates very freely on the sleeve 1 and drives the shaft 3 with very little, if any more wind power than is needed to rotate the ordinary 90 pin wheel alone.

The toy which the pin wheel rotates may be any kind of a figure. The figure of a monkey is illustrated in connection with Figures 1, 2, 3 and 4 and the figure of a 95 boy is illustrated in connection with Figures 6 and 7. These figures are made in one or more sections with one section being pivoted or anchored to the supporting stick and another section pivoted to the crank 4 of the 100 shaft 3. The figures are constructed of thin but stiff material such as cardboard, sheet

metal etc. and are cut out as illustrated to simulate figures, parts of which are moved to give action to them.

The arrangement of the toy figures with relation to the mounting of the pin wheel is such that the figure may be mounted on one side of the supporting stick while the pin wheel rotates without obstruction of any kind on the other side thereof. The pin wheel therefore rotates best when the figure is held so that it faces the child carrying the toy. In this position the pin wheel faces to the front away from the child and the figure faces to the rear toward the child. In this way the child can at all times observe the action of the figure while it is being operated by the rotation of the pin wheel.

The figure itself may be mounted on the stick in different ways and the action of the figure varied by making it in one, two or more parts, one of which may be rigidly held in place on the supporting stick or be pivotally mounted thereon.

The figure of the monkey illustrated in Figures 1 and 2 is made up in two parts 10 and 11 of which the part 10 comprises the head, body and legs of the monkey while part 11 comprises the arm thereof that is pivotally mounted to the body at 12. The body 10 of the figure is pivotally mounted at 13 on the bracket 14 that projects to one side of the supporting stick to which it is attached in any suitable manner. The arm 11 of the figure pivoted on the body is mounted on the crank 4 and forms the connecting link between the figure and the crank so that on the rotation of the crank by the pin wheel the figure is given a continuous rocking motion on the pivot 13.

The figure of the monkey illustrated in connection with the pin wheel toy construction of Figures 3 and 4, comprises three parts, the legs 16, body and head 17 and the arm 18. Of these the leg portion 16 is directly fastened to the supporting stick by means of nails or other suitable means that will hold this part of the figure rigidly on the stick. The body and head of the figure is pivotally mounted to the legs at 19 so that it can swing thereon while the arm 18 is pivotally connected to the body at 20 and connects the body with the crank 4 to which it is also connected. On the rotation of the pin wheel the crank 4 therefore moves the arm 18 which in turn sways the body and head of the figure back and forth simulating a climbing movement of the monkey.

In Figures 6 and 7 I have illustrated the figure of a body that is divided into three parts similar to the figure illustrated in Figures 3 and 4. However, instead of mounting the figure directly in contact with the supporting stick it is spaced from it by suitable spacing members 21 in the form of sleeves and surround the nails that pass thru the

figure and are driven into the supporting stick to support the figure thereon.

The pin wheels illustrated in Figures 9 to 12 inclusive are constructed to secure more power from the wheels for the rotation of the toy figure. This is done by providing a combination spacing and bearing member 50 at the front of the wheel in the center thereof with which the arms are spaced so as to secure maximum driving surface for the blades with a minimum frictional loss. The spacing member 50 may be provided only at the front of the pin wheel as illustrated in Figures 9 and 10 or it may be provided both at front and back of the wheel as illustrated in Figures 11 and 12.

I claim:

1. In a pin wheel toy, the combination of a supporting rod, a horizontal sleeve mounted in said rod and projecting from one side thereof, a shaft mounted to rotate in said sleeve and projecting from both ends thereof at opposite sides of said supporting rod, a crank formed at one end of said shaft, a pin wheel attached to the other end thereof, said sleeve spacing said crank from said pin wheel and preventing endwise movement of said shaft, said pin wheel being mounted to rotate on said sleeve.

2. In a pin wheel toy, the combination of a supporting rod, a horizontal sleeve mounted in said rod and projecting from one side thereof, a shaft mounted to rotate in said sleeve and projecting from both ends thereof at opposite sides of said supporting rod, a crank formed at one end of said shaft, a pin wheel attached to the other end thereof, said pin wheel being mounted to rotate on said sleeve, a movable toy figure mounted on said supporting rod on the side diametrically opposite to the side on which said pin wheel is mounted to rotate and means for connecting said toy figure with said crank to operate said toy figure on the rotation of said pin wheel.

3. In a pin wheel toy, the combination of a supporting rod, an elongated bearing provided in said supporting rod and projecting from one side thereof, a shaft mounted to rotate in said bearing, a pin wheel attached to said shaft, the rear of said pin wheel being mounted to rotate on said elongated bearing and the front of said pin wheel being supported on said shaft, a moving toy supported on said supporting rod, a connecting member between said moving toy and said shaft to operate said moving toy on the rotation of said pin wheel.

4. In a pinwheel toy, the combination of a supporting rod, a bearing provided in said supporting rod, a pin wheel mounted to rotate in said bearing a toy figure comprising a stationary part and a movable part, means for mounting said stationary part on said supporting rod, spacing sleeves interposed

between said stationary part and said supporting rod to hold said figure supported at a distance from said supporting rod, said movable part of said figure being pivoted on 5 said stationary part and being connected to said pin wheel to cause said movable part of the said figure to move on the rotation of said pin wheel.

5. In a pin wheel toy, the combination of 10 a supporting rod, a bearing provided in said supporting rod, a shaft mounted to rotate in said bearing and projecting from both ends of said bearing on opposite sides of said supporting rod, a pin wheel attached to

one end of said shaft on one side of said supporting rod, a crank formed on the other end of said shaft forming a shoulder on said shaft adapted to prevent the endwise movement of said shaft in one direction, a toy comprising a fixed and movable section, said 15 fixed section being attached to said supporting rod, said movable section being pivoted on said fixed section, and means connecting said movable section with said crank, to operate said movable toy on the rotation of 20 25 said pin wheel.

In testimony whereof I affix my signature.

JOHN HEBERLING.
